(57) CLAIM

The ornamental design for a pocket knife, as shown and described.

DESCRIPTION

FIG. 1 is a perspective view of a pocket knife showing my new design.

FIG. 2 is a right side perspective view of a pocket knife.

FIG. 3 is a left side perspective view of a pocket knife.

FIG. 4 is a front view of a pocket knife.

FIG. 5 is a rear view of a pocket knife.

FIG. 6 is a left side view of a pocket knife.

FIG. 7 is a right side view of a pocket knife.

FIG. 8 is a top view of a pocket knife; and,

FIG. 9 is a bottom view of a pocket knife.

The broken lines illustrate portions of the pocket knife that form no part of the claimed design.
